UNITED STATES PATENT OFFICE.

JOSEPH A. LAVIGNE, OF WORCESTER, MASSACHUSETTS.

BOTTLE-LABELING MACHINE.

Application filed June 22, 1925. Serial No. 38,770.

My invention relates to bottle labeling machines and has for its object to provide, in a machine of the class described, an improved wiper motion, whereby the labels 5 are more effectively applied to bottles. Another object of my invention is to so combine and coordinate the magazine and stripper motions of the machine that they may both be operated from a single actuating 10 member.

The above and further advantageous features of my machine will hereinafter more fully appear as the description proceeds. In the drawings,

Fig. 1 is an elevation from the left hand side of the machine embodying my invention.

Fig. 2 is an elevation from the right hand side of the machine shown in Fig. 1.

Fig. 3 is a front elevation of the machine shown in Fig. 1.

Figs. 4 and 5 are fragmentary views showing the elements of the wiper mechanism in different positions.

Fig. 6 is a detail view of a portion of the wiper mechanism.

Fig. 7 is a section on the line 7—7 of Fig. 3.

Like reference characters refer to like 30 parts in the different figures.

Referring more particularly to Figs. 1 and 2, the machine generally comprises a base 1 upon which is mounted an overhanging standard 2. A small standard 3 is also 25 mounted on the base 1 and with the standard 2 constitutes a support for the moving parts of the machine.

A main drive shaft 4 passes through the standards 2 and 3 which provide suitable 40 bearings for it, indicated by the reference numerals 5 and 6, the shaft 4 being driven in any suitable manner, as by a pulley 7. The other essential elements of the machine are a magazine 8 for the labels, picker arms 45 9 adapted to take labels from the magazine, and a stationary bottle rest 10 to support the bottle or article 11 to be labeled. As clearly shown in Figs. 1 and 2, the magazine 8 is offset from the rest 10 and the picker arms 9 are adapted to move a label from the magazine 8 to a position directly over the bottle or article 11, whereupon the label is applied 50 by the stripper 53 and wipers 87, see Fig. 3.

In labeling machines of the type to which 55 my invention relates there are four main motions respectively, controlling the maga-

zine, the picker, the stripper and the wiper, and as my invention resides in the correlation of these motions, one to another, the motions will now be particularly described 60 in detail, starting with the picker motion.

The pickers 9 are actuated from the main shaft 4, which for this purpose, carries an end cam 12 with a roller 13 on an arm 14 in engagement with the surface of cam 12. 65 The arm 14 is attached to a slide 15 reciprocable in guideways 16, and pivotally attached to the slide 15 is a short link 18 connected to a lever 19, which carries the picker arms 9. A spring 17 which connects the 70 lower portion of lever 19 to bracket 21 acts to pull the slide 15 to the left, Fig. 1, to keep the roller 13 on the cam 12, and it will be apparent that as the shaft 4 revolves, the picker arms 9 will be oscillated about 75 the pivot 20.

The adhesive applying roll motion is operated from a track cam 22 carried by the main drive shaft 4, a roller 23 fitting in the track of the cam 22, being carried by a 80 yoke 24 which straddles the shaft 4 and is constrained to receive a vertical motion from the cam 22. At the same time the yoke 24 is held from rotation about the axis of shaft 4 by a link yoke 26, the upper part 85 of which is received between the ends of a pair of bell-crank levers 27, 27. Thus as the shaft 4 revolves, the roller 23, travelling in the track of the cam 22, imparts a positive vertical rectilinear motion to the yoke 24, which motion is transmitted to the bell-crank levers 27, 27, thereby oscillating them 90 about the pivot shaft 28. At the upper ends of the bell-crank levers 27, are pivotally attached a pair of link rods 33, which serve 95 to reciprocate a pair of slide rods 34, received in brackets 35, attached to the standard 2. The connection between the link rods 33, 33, and the slide rods 34, 34, comprises collars 36 adjustable on the rods 34 by means 100 of set screws 37, each collar 36 providing a pivot pin 38 for one of the rods 33. The slide rods 34, 34, have enlarged end portions, or caps 39, 39, which constitute bearing brackets for a shaft 40 received therebetween, which shaft 40 carries an adhesive roll 41, by means of which adhesive is placed 105 on the picker arms 9 at each cycle of operation of the machine.

In order to supply the roll 41 with adhesive, there is provided a reservoir 42 which may be of any desired construction,

and within which is rotatably mounted an adhesive supply roll 43. For the purpose of driving the roll 43 a helical gear 44 is keyed to the shaft 4 in mesh with a helical gear 30 carried by the pivot shaft 28 which is thus rotated independently of the levers 27. A sprocket gear 32 at the other end of shaft 28, by means of a sprocket chain 45, drives a sprocket 46 keyed to a short shaft 47 which also carries a spur gear in mesh with a large spur gear 49 outside the reservoir 42, for driving the supply roll 43 through a shaft 50. A small spur gear 51 is keyed to the shaft 40 so that when the adhesive roll 41 is in the position shown in Fig. 2, the gears 49 and 51 are in mesh, whereas when the parts are in the position shown in Fig. 1, they are out of mesh. Thus the adhesive supply roll 43 is rotated continuously by the gearing just described, while the adhesive applying roll 41 is only driven when in the position shown in Fig. 2 that is, when in contact with the adhesive supply roll 43.

Considering now the magazine 8 and stripper 53, my invention contemplates the use of a cam 52 affixed to the main shaft 4 for controlling the movement of both these elements, as will now be described. A roller 54 rides on the peripheral surface of cam 52, this roller being carried by the forked end of a vertical rod 55. The lower portion of this rod 55 is square in cross section and is received in a guideway 56 which is desirably formed in a projection cast onto the standard 2; thus the rod 55 is held to vertical reciprocatory motion and is at the same time prevented from turning. The upper part of rod 55 is round in cross section and the break between the round and square portions provides a shoulder 57, against which a spring 58 bears. A bracket 59 attached to the standard 2 receives the round part of rod 55 and serves to limit the position of the upper end of the spring 58 which thus presses the rod 55 downwardly. A master lever 60 is pivotally mounted on the standard 2 by means of a stud 61 and the left hand end of this master lever 60, Fig. 1, is attached to the rod 55 by a pin and slot connection 62. This master lever 60 controls both the magazine and the stripper motions.

The stripper 53 in my improved machine is vertically reciprocable, and for this purpose it is carried by the lower end of a square plunger 63 received in a square guideway 64 which is desirably formed in an end projection 65 cast integral with the standard 2, as shown. The upper end of the plunger 63 has a horizontal hole through which extends a stud 66, with a boss 66^a at its outer or left hand end, see Fig. 3. This stud 66 is adapted to turn in the plunger 63 and the boss 66^a is drilled to receive an operating rod 67. At the upper end of rod 67 is a collar

68 preferably attached by means of a set screw, and a spring 69 surrounds the rod 67 between the collar 68 and the boss 66^a. A second collar 70 is placed below the boss 66^a and the lower end of rod 67 is attached to the right hand end of master lever 60, Fig. 1, by means of a fork and pin connection 71. Thus as the master lever 60 is oscillated, the plunger 63 carrying the stripper 53, is reciprocated by the connections described. The stripper 53 is pivotally attached to an upper member 72 carried by the plunger 63, so that when the stripper proper strikes the bottle it may adjust itself to lie flat on the surface of the bottle, in case the bottle is not exactly level. A spring 73 is preferably interposed between the stripper 53 and member 72, so that this adjustment will always be in one direction.

The magazine 8 shown in the accompanying drawings, does not differ materially from magazines already known in this art, and for the purpose of understanding the present invention, it is sufficient to state that the magazine shown in Figs. 1 and 2 is adjustable in every required manner; that is to say, the magazine prongs 74 may be lowered or raised with respect to a body portion 75 and the prongs 74 may be spread apart or brought together in two dimensions to accommodate different shapes of labels. The body portion 75 of magazine 8 is attached to a slide 76 carried by inclined guideways 77 in a bracket 78 attached to the standard 2, and as clearly shown in Fig. 1, a pivoted link 79 connects slide 76 to a bell-crank lever 80 pivoted on the master lever stud 61. The master lever 60 carries a segment 81 which provides pins 82 and 83 at its upper and lower extremities respectively, and during the normal operation of the machine the right hand end of lever 80 rests against the upper pin 82 by reason of the fact that the weight of magazine 8 and slide 76 is always trying to turn the lever 80 in a counterclockwise direction, as in Fig. 1. Consequently when the master lever 60 turns in a clockwise direction, it carries the lever 80 in the same direction, both levers being pivoted on the same stud 61, and the magazine 8 is lifted; but when the master lever 60 turns back again the magazine 8 is allowed to move downwardly through the action of gravity. Fig. 1 shows the magazine in its uppermost position and Fig. 2 shows it in an intermediate position, just after a label has been deposited on the pickers 9, the lowermost position being indicated in dotted lines in Fig. 2.

Lever 80 has a handle 84 at its right hand end, Fig. 1, while segment 81 has a hole 85 drilled therein at or near its middle portion; consequently when the operator wishes to try out the machine without actually placing any labels on bottles, in order, for

example, to see that all the motions are properly adjusted, he has only to pull the handle 84 downwardly until the lever 80 is below the hole 85 and then insert a pin in the hole 85. In this manner the magazine 8, although it will still move in proper relation to the stripper 53 as the machine turns over, will never move to its lowermost, or label depositing position.

Having described the picker, magazine and stripper motions, the wiper motion will now be described with reference to Figs. 3 to 7 inclusive. The entire motion of the wipers 87 is derived from a crank 88 attached to the front end of the shaft 4, which crank 88 is attached to a crosshead 92 by a link 89 and pins 90 and 91. As best shown in Fig. 7, the crosshead 92 is held to a vertical rectilinear path by guides 94 bolted to a pair of extensions 95, 95, of small standard 3, the crosshead 92 being provided with grooves 93 for the guides.

The top of crosshead 92 provides lugs 96, 96, on each side, to which are pivotally attached wiper arms 97, 97, by means of pins 98, 98. Each wiper arm 97 carries a roller 99, and a casting 100 supported on the small standard 3 provides a pair of tracks 101, 101, for receiving the rollers 99, 99. Each track 101 has an inside and an outside portion 101^a and 101^b respectively, and the rollers 99 traverse the inside portions 101^a as they descend, and the outside portions 101^b as they ascend. The position of the rollers 99 determines the angular relation of wiper arms 97 to the crosshead 92 and to each other, and it is obvious that when the rollers 99 are in the inside track portions 101^a, the wipers 87, 87, will be closer together than when rollers 99 are in the outside track portions 101^b.

As clearly shown in Fig. 4, the pivot pins 98, 98, are closer together than the rollers 99, 99, even when the latter are in the inside track portions 101^a, and from the general shape of the wiper arms 97, 97, it will be seen that their centers of gravity must lie outside the pins 98, so that when the rollers 99, 99, reach the bottom of the inside track portions 101^a, the wiper arms 97, 97, being unconstrained, will flop outwardly to place the rollers 99, 99, in the outside track portions 101^b, in which they ascend.

In order to shift the rollers 99 over to the inside track portions 101^a at the limit of their upward movement, a pair of disks 102 are rotatably mounted on shafts 103 located in recesses 104 coextensive with the tracks, each disk having a plurality of similar cut out portions 105. On the other side of casting 100 ratchets 106 are keyed or pinned to the shafts 103, and spring pressed pawls 107 press against these ratchets to permit them to turn in a single direction only, see Fig. 6. In Fig. 5 the ascending rollers 99

are shown about to engage in cut out portions 105 of the disks 102, which are free to turn in opposite directions. As the disks 102 turn, the rollers 99 fully enter the cut out portions 105 which receive them snugly as shown in Fig. 3. This figure shows the crank 88 in the vertical position, consequently the crosshead 92 is in its uppermost position, and further movement of the shaft 4 will draw the wiper arms 97 downwardly. In this position of parts, a ratchet tooth on each of the ratchets 106 has just gone beyond the edge of pawls 107, thus locking the ratchets as shown in Fig. 6; consequently the disks 102 cannot turn backwards. The rollers 99 therefore are constrained to ride off the flat part of the cut out portions 105 as the crosshead 92 moves down, and thus they enter the inside track portions 101^a at start of the downward movement of the wiper arms 97.

Starting with the parts of the machine in the position shown in Fig. 2 (full lines) there will now be described a complete cycle of operation. A gummed label 108 is already on the picker arms 9 and the latter are in substantially their lowermost position. The stripper 53 is descending and is about to pass between the picker arms 9, and as it does so, it will place the label 108 on the bottle 11 and hold it there. The picker arms 9 then move rapidly upward to the position of Fig. 1 and the wipers 87 move downwardly, as shown in Fig. 4, while the stripper 53 holds the label in place. The adhesive roll 41 then moves rapidly outward with the pickers 9 stationary, thus depositing a new coating of adhesive on them. As the roll 41 reaches its outwardmost position, the parts are in the position shown in Fig. 1 and the wipers 87 have practically completed their downward stroke. When the roll 41 returns to contact with supply roll 43, the stripper 53 rises rapidly from its lowermost position to its highest position, see the dotted line position of stripper in Fig. 2.

As the stripper 53 moves to its highest position, the magazine 8, by the operation of the master lever 60, moves to its lowermost position, the prongs 74 being shown in dotted lines in Fig. 2, in connection with the picker arms 9 also in dotted lines. The arms 9 remain stationary while the magazine 8 is lowered and the prongs 74 pass through convenient holes in the pickers. The lowermost label adheres to the picker arms 9 and flexes away from the prongs 74, leaving the rest of the labels undisturbed as the picker arms 9 descend with the label, and the magazine rises.

In Fig. 1 there is shown a foot pedal 109 at the end of a lever 110 which operates a clutch mechanism 111 through a link 112 and short lever 113. The clutch mechanism

111 need not be described, since it forms no part of my invention, and might be of any type desired. By this mechanism, the machine is adapted to come to a stop just at, or prior to, the position of parts shown in Fig. 2, and the operator may start the machine by stepping on the pedal 109. It will be noted that the gummed label is ready for deposit, and as soon as the wipers 87 have finished their stroke and the stripper 53 has started up, the operator may remove the labeled bottle and replace it with an unlabeled one. The cycle of operations just described is then repeated.

12 From the foregoing it will thus be seen that I have provided an improved bottle labeling machine in which the stripper and magazine motions are always in proper relation owing to the use of a master lever for actuating both motions. My improved arrangement also permits the magazine to be rendered inoperative temporarily for testing out the machine, without wasting labels.

13 The wiper motion of my machine is extremely effective for the reason that the wipers 87 travel in a different path when ascending and descending, and there is no danger of knocking a bottle off the bottle rest by the ascending wipers 87. The exact path of the wipers 87 being determined by a track cam, there will be no variation in their movement, and the mechanism that moves the rollers 99 which control the wiper arms 97 is extremely effective in shifting the rollers to the inside track for the downward movement of the wipers.

14 From the foregoing it is apparent that by my invention I have provided an improved bottle labeling machine which is extremely effective in operation, by reason of the coordination of the various motions of the machine. While I have shown my machine as employing a particular arrangement of parts for carrying out the various motions, obviously various minor changes and modifications can be carried out without departing from my invention.

I claim:

15 1. In a machine of the class described, the combination with a vertically reciprocating stripper and a movable label magazine adapted to deliver a label when moved to one extreme position, said magazine being offset with respect to the line of movement of said stripper, of means for operating

said stripper and magazine from a single actuating member.

2. In a machine of the class described, the combination with a vertically reciprocating stripper, a reciprocating label magazine having a non-parallel movement with respect to said stripper and a rotating shaft, of means for operating both said stripper and said magazine from a single actuating member connected to said shaft. 60 65

3. In a machine of the class described, the combination with pickers having an arcuate motion, a vertically reciprocating stripper and a label magazine inclined between the vertical and the horizontal and adapted to move rectilinearly to deposit a label on the said pickers, of a pivotally mounted lever for operating both said stripper and said magazine in timed relation with said pickers. 70 75

4. In a machine of the class described, the combination with pickers having an arcuate motion, a vertically reciprocating stripper and a label magazine inclined between the vertical and the horizontal and adapted to move rectilinearly to deposit a label on the said pickers, of a pivotally mounted lever for operating both said stripper and said magazine in timed relation with said pickers, and means for rendering said magazine inoperative to deposit labels on said pickers without disconnecting it from said lever. 80 85

5. In a machine of the class described, a vertically reciprocating member, a wiper arm pivotally attached to said member, a projection on said arm, an endless track adapted to receive said projection to control the angular position of said arm relative to said reciprocating member, and a disk with cut out portions to cause said projection to move first in one position of said track and then in the other. 90 95

6. In a wiper mechanism for bottle labeling machines, a pivotally mounted wiper arm, means for imparting a reciprocating movement to said arm, an endless track for causing said arm to travel in different paths as it reciprocates, and means for shifting said arm from one portion of the track to another at the end of its upward movement, the said arm being adapted to shift back by gravity at the end of its downward movement. 100 105

JOSEPH A. LAVIGNE.
